UNITED STATES PATENT OFFICE.

THOMAS TIMOTHY CHALONER, OF NEW YORK, N. Y.

RAILWAY-SWITCH.

SPECIFICATION forming part of Letters Patent No. 740,232, dated September 29, 1903.

Application filed March 18, 1903. Serial No. 148,381. (No model.)

To all whom it may concern:

Be it known that I, THOMAS TIMOTHY CHALONER, a citizen of the United States, and a resident of the city of New York, borough of Manhattan, in the county and State of New York, have invented a new and Improved Railway-Switch, of which the following is a full, clear, and exact description.

This invention relates particularly to improvements in railway-switches, an object being to provide a switch of simple construction that may be readily and positively shifted by a motorman or driver on a moving car.

I will describe a railway-switch embodying my invention, and then point out the novel features in the appended claims.

Reference is to be had to the accompanying drawings, forming a part of this specification, in which similar characters of reference indicate corresponding parts in both the figures.

Figure 1 is a plan view of a switch mechanism embodying my invention, and Fig. 2 is a perspective view showing the free end of the switch-tongue.

25 In the drawings, 1 2 designate the main rails of a track, and 3 4 the switch-rails. Mounted to swing at the end of the switch-rail 3 is a switch-tongue 5, the point 6 of which is held yieldingly and normally against the main rail 1, as here shown by means of a spring 7 surrounding a rod 8, movable in a boxing 9 and connecting with the tongue. From the point end the tongue is provided with an extension 10, which is curved slightly

35 inward, and the upper surface of this extension is below the plane of the top surface of the switch point or tongue, thus permitting the flanges of the car-wheels to pass over said projection and onto the tongue when a car 40 is to be run upon the switch. The switch-tongue is movable on a plate 11, attached to the track-ties, and pivoted to this plate 11 is a shifting dog 12, which engages with the projection 10 at the side adjacent to the rail.

45 1. The top surface of this dog 12 is substantially on a plane with the top surface of the projection 10.

The shifting device consists of a shoe 13, carried by a car. This shoe is pointed at its

end, and if it is desired to pass the car along 50 the main track the said shoe is lowered to engage with the dog 12, which will force the switch-tongue out of engagement with the main rail, permitting the car to pass. If the car is coming from the opposite direction, it 55 is obvious that the flange of the wheel will swing the tongue inward against the resistance of the spring.

Having thus described my invention, I claim as new and desire to secure by Letters 60 Patent—

1. In a railway-switch, a switch-tongue having an extension from its point end, the top of said extension being below the plane of the top surface of the tongue, and a swing- 65 ing device at the side of the track-rail for engaging said extension.

2. In a railway-switch, a switch-tongue yieldingly held against a main rail, an extension from the point end of said tongue, 70 the upper surface of said extension being below the plane of the top of the tongue, and a swinging dog at the side of the track-rail for engaging with said extension.

3. In a railway-switch, a switch-tongue, a 75 spring for holding the tongue yieldingly in connection with a main rail, an extension from the point end of the tongue and below the plane of the top thereof, a pivoted dog for engaging with said extension, and a device carried by a car for engaging with said dog to swing the tongue.

4. In a railway-switch, a plate at one side of the track-rail, a switch-tongue pivoted on said plate, a curved extension from the free 85 end of the tongue below the plane of the top thereof, a dog pivoted to said plate and engaging with said projection, and means for holding the tongue yieldingly against the rail. 90

In testimony whereof I have signed my name to this specification in the presence of two subscribing witnesses.

THOMAS TIMOTHY CHALONER.

Witnesses:

FRANK J. KARSHICK,
WILLIAM BARTON.
